UNITED STATES PATENT OFFICE.

JOHN M. JAMES AND CHARLES C. JAMES, OF NEW YORK, N. Y.

ADVERTISING APPARATUS.

1,333,920.

Specification of Letters Patent. Patented Mar. 16, 1920.

Application filed November 19, 1918. Serial No. 263,124.

To all whom it may concern:

Be it known that we, JOHN M. JAMES and CHARLES C. JAMES, both citizens of the United States, and residents of the borough 5 of Manhattan, county and State of New York, have invented certain new and useful Improvements in Advertising Apparatus, of which the following is a specification.

Our invention relates to improvements in 10 advertising apparatus, and although adapted for many forms of advertising and display devices and other purposes, it is particularly advantageous for advertising or displaying titles of acts in vaudeville 15 theaters and the like.

One object of our invention is to provide an improved arrangement whereby a series 20 or plurality of cards or supports with advertising or display matter thereon, may be brought into display position by endless conveying means, one by one, but in which the cards or the like are automatically disengaged from the conveying means and supported in such a manner that their arrangement 25 in the series may be easily changed and one or more of them removed or others added thereto in any desired order, even while the apparatus is in operation. Another object of our invention is to provide 30 an apparatus for displaying such advertising cards or the like, having an endless conveyer for moving the cards or the like into display position, and improved means for automatically stopping the movement of the 35 cards or the like when they have reached the desired display position.

Further objects, features and advantages will more clearly appear from the detailed 40 description given below taken in connection with the accompanying drawings which form a part of this specification.

In the drawings, Figure 1 is a front view of an apparatus embodying our improvements in their preferred form;

Fig. 2 is vertical section of the same taken 45 on the line 2—2 of Fig. 1;

Fig. 3 is a vertical section taken on the line 3—3 of parts shown in Fig. 2;

Fig. 4 is a transverse section taken on the 50 line 4—4 of parts shown in Fig. 2;

Fig. 5 is a detail in perspective of a portion of one of the endless conveyer chains with its hook engaging one of the rods supporting one of the advertising cards or the 55 like.

Fig. 6 is a diagram of the electric circuit connections.

Referring to the drawings, 7 and 8 represent two upright members for suitably supporting the apparatus. 9 and 10 are two 60 side members of the apparatus supported by and secured to the uprights 7 and 8 respectively, as by bolts 10^a. The side member 9 is provided with an upright front guide flange 11 and an upright rear guide 65 flange 12 and an inclined bottom guide flange 13, all of which parts may be conveniently made of sheet metal. The flanges 11, 12 and 13 extend inwardly and are placed directly opposite similar flanges on the opposite side member 10, the front flange of which is indicated at 14. Within each of side members 9 and 10 there is placed a member 15 having an inclined top edge 16. The members 15 are suitably spaced 70 from the flanges 11, 12, and 13 to provide upright and bottom guide grooves therebetween as indicated at 17, 18 and 19. Secured to the front side of the member 15 is a right angled flange member 20 with its 75 flange 21 extending parallel with the flange 11 and serving as a guide for the upward passage of the endless conveyer chain 22. At the rear side of the member 15 there is secured thereto another right-angled flange 80 member 23 having its flange 24 extending parallel with the flange 12 to form a guide for the downward passage of the chain 22. While the upper edge of the member 15 inclines downwardly as indicated at 16, yet 85 at the lower end thereof it is curved upwardly and around to the side edge thereof as indicated at 25.

It will be understood that the side member 10 is similarly arranged with suitable guide 95 members and a similar endless conveyer chain. Arranged on and supported by the stationary inclined surface 16 is a series or plurality of rods 26 having their ends bearing on the inclined surfaces 16 respectively. 100 Each of these rods carries an advertising or display card 27 or the like, the cards being pivotally secured to the rods 26 by means of wire loops or hooks 28, bent into grooves 29 in the rods 26 (see Fig. 6). The endless conveyer chain 22 passes over a driving sprocket 30, thence upwardly over a sprocket 31 and then down underneath a sprocket 32, up over a sprocket 33 and down about sprocket 34 to the driving sprocket 30. Similar sprockets 110

are provided in the other side 10 of the apparatus.

Each of the endless conveyer chains in the side members 9 and 10 is provided with two links each having a hook with a long arm 35 and short arm 36. As one hook on each side of the apparatus passes up over the sprocket 33, such hooks will engage the respective ends of the lowermost rod 26 at the 10 end of the series on the support 16 as indicated at 37 in Fig. 2, and carry such rod up over the sprockets and down the guide ways 18, and then around the sprockets 34 and down the inclined guideways 19 and then 15 around the sprockets 30 and up the guide- ways 17. During this movement the rod is prevented from coming out and becoming disengaged from the hooks since the flanges 12, 13 and 11 hold the ends of the rod 26 in 20 between the arms 35 and 36 of the hooks. When the rod reaches the position indicated at 38 on Fig. 2, it supports its advertising card or the like in suitable display position. Upon further movement of the endless conveyer chains 22, the hooks carrying the rod 38 up over the sprockets 31 where it becomes supported by the ledges 16 and as the chains 22 convey the hooks downwardly, the rod 38 is deposited upon the inclined supports 16 and is free from the hooks on the conveyer. Further continued movement of the conveyer chains, however, causes hooks to pass under idlers 32 and then up over the sprockets 33 where the hooks engage the 35 next rod 26 of the series and will convey it through the apparatus to display position in a similar manner.

The two side members 9 and 10 are rigidly tied together by the rods 39, 40 and 41. 40 Springs 42 extend down over the ends of the rods 26 on the supporting edges 16, but do not prevent the rods from rolling down said inclined supporting edges so as to assume the proper position at the bottom of the inclined edge where they will be engaged by the hooks on the conveyer chains to be carried over the edges 25 and through the apparatus as above described. When the hooks on the conveyer chain engage the lowest rod 50 on the supporting ledge 16 at the lower end of the series, the lower end of the spring 42 is forced upwardly slightly until the ends of the rods are forced into the hooks between the arms 35 and 36 thereof. The sprocket 55 wheels and conveyer chain in the side 10 are driven by means of shaft 43 which carries the sprockets 30, said shaft extending through the side 9 and having on its outer end sprocket 44 driven by a sprocket chain 60 45, driven by electric motor 46 (see Fig. 1). By reason of the connections described the motor 46 will drive both conveyer chains at exactly the same speed and always in step, so that the hooks on the conveyer chains will 65 engage the opposite ends of each supporting

rod 26 simultaneously, and the rods 26 maintained level. In order to maintain the conveyer chains taut the idlers 32 are carried upon slotted plates 47, slidably mounted upon the sides of the apparatus and 70 normally pulled downwardly by tension springs 48.

In order that the supporting rods and display cards carried thereby may be stopped in their movement when they reach 75 the proper display position, we provide a lever 50 pivoted at 51 and having a long arm 52 adapted to be engaged by one end of each rod 26 just prior to its reaching the proper display position. Pivoted 80 connected to the lever 50 at 53 is a link 54 having its lower end pivotally connected to a lever 55 at 56. Lever 55 carries a pawl 57 adapted to operate a ratchet 58. A tension spring 59 normally pulls the lever 55, 85 link 54 and lever 50 downwardly holding the short arm 60 of the lever 50 against a stop 61. As the supporting rod 26 indicated at 38, in Fig. 2 is moved upwardly by the conveyer chain it engages the lever arm 52, 90 and causes it, through the link 20 to operate pawl 57 and move the ratchet 58 one notch ahead. This operation of the ratchet 58 is designed to operate a three way snap switch 62 in a manner well understood by those 95 skilled in the art, so as to open the motor circuit and thus deenergize the motor and arrest the movement of the rod at 38 so as to stop the movement of the advertising card in the proper display position, it being understood that the display cards are looked at in the direction indicated by the arrow 63 in Fig. 2. Another three way switch 64 is provided in the circuit connections to the motor which circuit connections 100 are more clearly illustrated in the diagram shown in Fig. 6. In this diagram the motor 46 is shown as energized from an electric battery 65. However, any suitable source may be used. The three way switch 62 is 105 provided with four contacts 66, 67, 68 and 69 and with a diagonal snap switch member 70. The three way switch 64 is provided with four contact terminals 71, 72, 73 and 74 and with a diagonal snap switch member 110 75. Contacts 66 and 67 are connected together by conductor 76, and contact 67 is connected to one side of the motor by conductor 77, the other side of the motor being connected to the battery by conductor 78. 115 Contact 71 is connected to the other side of the battery by conductor 79 and to the contact 72 by conductor 80. Conductor 81 connects the contacts 69 and 74 and conductor 82 connects the contacts 68 and 73. With the contacts and switch members in the position shown in Fig. 6 it will be seen that the motor 46 will be energized and operate the 120 endless conveyer chains so that the hook members thereon will pick up one of the 125 130

rods 26 at the end of the series and convey it to the position indicated at 38 in Fig. 2. As the end of the rod engages and moves the lever 52 upwardly, it operates the snap 5 switch member 70 by means of the pawl and ratchet 57 and 58 so that the switch member 70 occupies the position shown in dotted lines in Fig. 6, thereby opening the circuit of the motor and stopping the movement of the card 26, pivotally supported by the rod 38, in display position.

When it is desired to bring the next card into position, the switch 64 is operated, as by hand, to throw the switch member 75 to the position shown in dotted lines in Fig. 6 whereupon the motor is again energized and the hook members carrying the rod 38 are carried over the sprockets 31, where they deposit supporting rod 38 upon the inclined supporting ledge 16 and free of the endless conveyer chains and it rolls down the inclines 16 to the rear end of the series of rods 26. The hook members then pass under the idler sprockets 32 and then upwardly where they engage the next rod of series and carry it down the guide slot 18. During this movement the other pair of hook members convey the rod 83 (see Fig. 2) with the advertising card supported 15 thereby, down the inclined slots 19 under the sprockets 34 and 30 and up vertical slots 17 to the display position. When it reaches the display position the ends of this rod 83 will operate the lever 52 to deenergize 20 and stop the motor as above described, by throwing the switch member 70 to the position shown in full lines in Fig. 6, it being remembered that at this time the switch member 75 is in the position shown in dotted lines in Fig. 6.

It will be understood that the front of the apparatus is preferably covered with a suitable frame, having an opening through which the advertising or display matter on 45 the card in display position, is seen. When used for announcing vaudeville acts, advertising cards may be alternated with cards announcing the acts.

From the above it will be seen that the 50 conveyers pass down and below the supporting means or racks 16 when moving in both directions from one end of the support to the other so that the rods 26 with their respective cards may be easily removed from 55 the supporting surface 16 and other cards inserted in their places and in any order desired, without interfering in any way with the operation of the apparatus. The endless conveyer picks up the display members 60 and forces them off from the inclined racks 16, separately and one by one, from the lower end of the series, and carries them down below said racks and then up and deposits them on the racks 16 at the other 65 and upper end thereof. The rods are de-

posited on the inclined racks in the following manner: As the forked rod-carrying members 35 travel over the sprockets 31 and start downwardly in a direction at a sharp angle to the inclined racks, the forked 70 members are thereby tilted, and due to the tilting and the fact that the then lower fork is short, the rods are free to move out of the fork recesses onto the inclined racks 16 during which time and for a short period thereafter, the longer fork 35 will engage the rods to positively force them along the upper portion of the inclined racks so as to insure not only the simultaneous transfer of both ends of the rods from the forks 80 to the racks, but also the positive and simultaneous movement of each end of the rod after it is deposited on the racks so as to avoid any jamming of the rods in the operation of transferring or depositing them from 85 the hooks to the inclined racks on which they are free to slide down into position at the other end of the series and ready to be again conveyed to display position. The rods roll easily in the wire members 28 90 which pivotally support the cards 26 thereon. The hook or forked members 35, 36, support the display members on one side of the forks when moving upwardly and on the other side of the forks when traveling 95 downwardly. It will be noted that the apparatus is free from mechanism which would bend the display members or change the position of the display members from the vertical during their travel from one end of 100 the series on the racks to the other end of the series on the racks. In each case the movement of the display cards is automatically stopped by the movement of the conveyer when the cards reach the display position, the switch 62 being opened independent of the position the switch member 75 may be in.

While we have described our improvements in great detail and in connection with 110 a preferred embodiment thereof, we do not desire to be limited to such details or embodiments as many changes and modifications may be made and in the invention embodied in widely different forms without 115 departing from the spirit and scope thereof in its broader aspects.

What we claim as new and desire to secure by Letters Patent, is:—

1. In an apparatus of the class described, 120 a series of display members, a stationary support for the same, and an endless conveyer having means for picking said members separately from one end of the series and carrying them down under said support and then up, retaining them while being conveyed from one end of the support to the other, and then depositing them upon said support free of the conveyer at the other end of the series, the apparatus being 130

adapted to permit the display members to hang substantially vertically throughout their travel on the conveyer.

2. In an apparatus of the class described, 5 the combination of a series of display members, a rack device for normally holding the series of display members one back of another, and endless flexible conveyers having means forcing said members separately off 10 from said rack device at one end of the series and carrying them down under said rack device and then up, retaining them while being conveyed from one end of the rack device to the other, and then depositing them upon said rack device free of the 15 conveyer at the other end of the series.

3. In an apparatus of the class described, 20 a series of display members, a stationary support for the same, and an endless conveyer having means for picking said members separately from one end of the series and carrying them down under said support and then up and depositing them upon said support free of the conveyer at the other end of the series, and means operated when the 25 display members reach a predetermined position, for automatically stopping the conveyer.

4. In an apparatus of the class described, 30 the combination of a series of display members, a rack device for normally holding the series of display members one back of another, and endless flexible conveyers, said 35 conveyers having forked members for engaging the display members and forcing said members separately off from said rack device at one end of the series and carrying them down under said rack device and then up and depositing them upon said rack 40 device free of the conveyer at the other end of the series, said forked members supporting the display members on one side of the forks when traveling upwardly and on the other side of the forks when traveling 45 downwardly and rigid guide means along a portion of the path of the conveyer co-operating with said forked members for maintaining the display members in engagement with the conveyer.

5. In an apparatus of the class described 50 the combination of inclined racks, a series of display members with rods attached thereto for supporting them on the inclined racks and flexible conveyers adapted to pick 55 up said members separately from one end of the series on said racks and carry them down under said racks then up, retaining them while being conveyed from one end of the racks to the other, and then depositing 60 them on said racks at the other and upper end of the series.

6. In an apparatus of the class described 65 the combination of inclined racks, a series of display members with rods attached thereto for supporting them in vertical

position from the inclined racks and flexible conveyers adapted to pick up said members separately from one end of the series on said racks and carry them down under said racks then up and deposit them on said racks at the other and upper end of the series, means operated when the display members reach a predetermined position for automatically stopping the conveyer, and control means for starting the conveyer. 70 75

7. In an apparatus of the class described the combination of a series of display members, a rack device for normally holding the series of display members one back of another, and endless flexible conveyers having 80 means forcing said members separately off from said rack device at one end of the series and carrying them down under said rack device and then up, retaining them while being conveyed from one end of the rack device to the other, and then depositing them upon said rack device free of the 85 conveyer at the other end of the series, said conveyer then passing downwardly and below the rack device to the other end thereof. 90

8. In an apparatus of the class described the combination of two inclined racks positioned at the upper part of the apparatus, a series of display members, supported vertically from said racks, two endless conveyer chains, a sprocket for each at the upper end of the racks, a sprocket for each at the lower end of the racks an intermediate sprocket for each below the racks, and two other sprockets for each, below said racks, and means driving said conveyer chains and causing them to force off and pick up said display members one by one from the lower end of the racks and carry them down under said racks and over said last mentioned 100 sprockets and then upwardly, retaining them while being conveyed from one end of the racks to the other, and then depositing them upon the upper end of said racks. 105

9. In an apparatus of the class described, 110 a series of display members, a stationary support for the same, and an endless conveyer having means for picking said members separately from one end of the series and carrying them down under said support free of the conveyer at the other end of the series, an electric motor for driving said conveyer, a switch operated responsive to movement of the conveyer for stopping the motor when a display member has 115 reached display position and a switch for again causing the motor to be energized, through said first mentioned switch and independent of the position thereof.

10. In an apparatus of the class described, 120 the combination of a series of display members, a stationary support for the same and an endless conveyer having means for picking said members one by one from one end of the series on said support and carrying 125 130

them down under said support and then up and then depositing them on said support at the other end of the series, said means comprising a forked member adapted to engage means projecting from the display members, and rigid guide means coöperating with the forked members to maintain the display members on the conveyer substantially during the entire downward and transverse movement of the display members when traveling on the conveyer from one end of the series to the other end thereof.

11. In apparatus of the class described, the combination of a series of display members having supporting projections, racks for normally supporting said display members from said projections one back of another, endless conveyers having forked members for forcing said members separately off from said racks at one end of the series of members and carrying them down under said racks and then up and depositing them upon said racks from the conveyer at the other end of the series of members, and means for 25 guiding said conveyers downwardly and below said racks to the other end thereof, said forked members having their inner contour substantially shaped but with the forward fork of each shorter than the other, said downward movement of the conveyers as they come from the back to the front end of the racks and the position of the racks being such that the supporting projections of the display members as they are deposited 30 on the racks, are forced along the racks by the rear fork of each forked member.

12. In apparatus of the class described, the combination of a series of display members having supporting projections, racks for normally supporting said display members from said projections one back of another, endless conveyers having forked members for forcing said members separately off from said racks at one end of the 45 series of members and carrying them down under said racks and then up and depositing them upon said racks from the conveyer at the other end of the series of members, and means for guiding said conveyers downwardly and below said racks to the other end thereof, said forked members having their inner contour substantially shaped but with the forward fork of each shorter

than the other, the upward movement of said conveyers toward the front end of the 55 racks and the position of the racks with respect thereto being such that the short forward fork of each forked member passes by the supporting projections of the first display member on the rack while the following 60 fork of each forked member engages the said projections to pick them off of the rack.

13. In an apparatus of the class described the combination of a plurality of display members, an endless conveyer having means for conveying the display members, one by one, to display position, an electric motor for driving said conveyer, connections from said motor to a source of electrical energy for energizing the motor, two three way switches 70 in said connections, and means whereby one switch is operated responsive to the movement of the conveyer to stop the motor when a display member has reached display position, operation of the other switch being 75 adapted to cause the motor to be operated through the first switch independent of the position thereof.

14. In an apparatus of the class described, the combination of a plurality of display 80 members adapted to be displayed sequentially, electrically controlled means for causing said members to be moved from one position to another, a 3-way switch operated responsive to the movement thereof for automatically stopping said means, and another 85 3-way switch manually controlled and electrically connected with the first for starting said electrically controlled means through said first switch and independent 90 of the position thereof.

15. In an apparatus of the class described, the combination of display means for displaying a plurality of signs sequentially, an electric motor for operating said display 95 means, a switch operated responsive to the movement of said display means for automatically stopping the motor, and another switch electrically connected with the first for causing the motor to be energized 100 through said first switch and independent of the position thereof.

In testimony whereof we have signed our names to this specification.

JOHN M. JAMES.
CHARLES C. JAMES.

It is hereby certified that in Letters Patent No. 1,333,920, granted March 16, 1920, upon the application of John M. James and Charles C. James, of New York, N. Y., for an improvement in "Advertising Apparatus," an error appears in the printed specification requiring correction as follows: Page 5, line 28, claim 11, and line 52, claim 12, for the words "substantially shaped" read *substantially L-shaped*; and that the said Letters Patent should be read with this correction therein that the same may conform to the record of the case in the Patent Office.

Signed and sealed this 20th day of April, A. D., 1920.

[SEAL.]

M. H. COULSTON,
Acting Commissioner of Patents.

Cl. 40—78.
